UNITED STATES PATENT OFFICE

FRANK J. McDONOUGH, OF CHICAGO, ILLINOIS, ASSIGNOR TO GLASER, CRANDELL CO.,
OF CHICAGO, ILLINOIS, A CORPORATION OF ILLINOIS

DESIGN FOR A FOOD PRODUCT CONTAINER

Application filed June 12, 1931. Serial No. 40,176. Term of patent 14 years.

To all whom it may concern:

Be it known that I, FRANK J. McDONOUGH, a citizen of the United States, residing at Chicago, in the county of Cook and State of Illinois, have invented a new, original, and ornamental Design for a Food Product Container, of which the following is a specification, reference being had to the accompanying drawings, forming part thereof.

I claim:
The ornamental design for a food product container as shown.

In witness whereof, I hereunto subscribe my name, this 10th day of June, 1931.

FRANK J. McDONOUGH.
